[57] CLAIM

The ornamental design for a water purification pitcher, as shown and described.

DESCRIPTION

FIG. 1 is a top perspective view of a water purification pitcher showing our new design;

FIG. 2 is a side view thereof, the opposite side of that shown being a mirror image;

FIG. 3 is a top view thereof;

FIG. 4 is a bottom view thereof;

FIG. 5 is a front view thereof;

FIG. 6 is a back view thereof;

FIG. 7 is a perspective view of our new design for a water purification pitcher;

FIG. 8 is a side view thereof, the opposite side of that shown being a mirror image;

FIG. 9 is a top view thereof;

FIG. 10 is a bottom view thereof;

FIG. 11 is a front view thereof; and,

FIG. 12 is a back view thereof.

The broken line showing of a pour tray, filter, and cover in FIGS. 1–6 are for illustrative purposes only and forms no part of the claimed design.
